UNITED STATES PATENT OFFICE.

ERNEST D. CLARK, OF WENONAH, NEW JERSEY, ASSIGNOR OF ONE-HALF
TO E. WARD WILKINS, OF PHILADELPHIA, PENNSYLVANIA.

STEREOPTICON.

SPECIFICATION forming part of Letters Patent No. 759,671, dated May 10, 1904.

Application filed November 30, 1903. Serial No. 183,141. (No model.)

To all whom it may concern:

Be it known that I, ERNEST D. CLARK, a citizen of the United States, residing at Wenonah, in the county of Gloucester, State of New Jersey, have invented a new and useful Improvement in Stereopticons, of which the following is a specification.

My invention relates to stereopticons.

It consists of means for displaying pictures by means of an electric lamp, for supporting said lamp within the tube or body of the device, and for conserving the electric energy.

It further consists in providing a complete convenient device for the purpose named, including a battery for supplying current to the lamp.

It further consists of novel features of construction, all as will be hereinafter fully set forth.

Figure 1 represents in elevation a device embodying my invention. Fig. 2 represents sections through the lines *x x* and *y y*, respectively, except that the latter figure represents the box as closed.

Similar numerals of reference indicate corresponding parts in the figures.

Referring to the drawings, 1 designates a box provided with a cover 2 and a handle 3, by which it may be carried. Hinged to the front side 4 of the box is a shelf 5, carrying a stereopticon-tube 6, containing the usual lenses 7, reflector 8, and slide-holder 9. Supported within the tube 6 is an incandescent electric lamp 10, so placed that its filament is substantially in the focus of the reflector 8. Wires 11 12 lead from the lamp 10, including in their circuit a dry battery 13 and a push-button 14. A partition 15 in the box 1 affords convenient storage for slides 16.

The operation is as follows: When it is desired to use the lantern, the box 1 is opened and the shelf 5 raised and supported by the leg 17, as shown in Fig. 1. When the slide 16 is in position in the holder 9, the button 14 is pushed in to complete the electric circuit, and the light from the lamp 10 illuminates the picture. Before the slide is moved or withdrawn the light is extinguished, so that no cur-

rent is wasted and no movement or jerking of the picture is shown on the screen. When the exhibition is concluded, the whole working apparatus may be inclosed in the box 1 and conveniently carried by the handle 3.

The advantages of my device are, first, its completeness in that the projector, the lamp, and the battery are conveniently mounted in a very small box, which may also be used to carry a collection of slides; second, that the projector or stereopticon folds down within the box, where it is perfectly protected, and may immediately be raised to an operative position; third, that the box may be easily handled and may throw its picture in any direction, horizontal or vertical, thus enabling the operator to use the ceiling of a room as a screen; fourth, the inclusion of the push-button with the device, which prevents any unnecessary waste of electric energy and is so placed that it can be readily manipulated by the hand which supports the complete device.

It is evident that various changes may be made by those skilled in the art which will come within the scope of my invention, and I do not, therefore, desire to be limited in every instance to the exact construction herein shown and described.

Having thus described my invention, what I claim as new, and desire to secure by Letters Patent, is—

1. A portable stereopticon outfit comprising a box, a hinged shelf within said box, a stereopticon mounted on said shelf, an incandescent electric lamp in said stereopticon, a storage battery in said box and wired to said lamp and a push-button in the circuit of said lamp and battery.

2. A portable stereopticon outfit comprising a box, a shelf hinged within said box and adjacent the upper edge of one side thereof, a stereopticon mounted on said shelf so as to be alternatively placed within and above the sides of said box, an incandescent lamp in said stereopticon, an electric battery in said box and wired to said lamp and a push-button in the circuit of said lamp and battery.

3. A portable stereopticon outfit comprising

ing a box, a partition in said box forming a compartment for slides, a shelf hinged within said box and adjacent the upper edge of one side thereof, a stereopticon mounted on said shelf so as to be alternatively placed within and above the sides of said box, an incandescent electric lamp in said stereopticon, an elec-

tric battery in said box and wired to said lamp and a push-button in the circuit of said lamp and battery.

ERNEST D. CLARK.
